UNITED STATES PATENT OFFICE

CHARLES R. HARDY, OF MOUNT VERNON, NEW YORK, ASSIGNOR TO THE SUPERHEATER COMPANY, OF NEW YORK, N. Y.

DESIGN FOR A FEED-WATER HEATER

Application filed January 10, 1931. Serial No. 38,265. Term of patent 14 years.

To all whom it may concern:

Be it known that I, CHARLES R. HARDY, a citizen of the United States, residing at Mount Vernon, in the county of Westchester and State of New York, have invented a new, original, and ornamental Design for Feed-Water Heaters, of which the following is a specification, reference being had to the accompanying drawings, forming part thereof, and in which—

Fig. 1 is a perspective view of a feed-water heater showing my new design.

Fig. 2 is a front elevation of the feed-water heater shown in Fig. 1.

Fig. 3 is a side elevation of the feed-water heater shown in Fig. 1.

I claim:

The ornamental design for a feed-water heater, as shown.

CHARLES R. HARDY.
